Specification of Letters Patent. Patented Dec. 21, 1915.

Application filed August 19, 1912. Serial No. 715,698.

To all whom it may concern:

Be it known that we, REUBEN E. BECHTOLD and ANDREW D. WYCKOFF, citizens of the United States, residing at Fort Wayne, in the county of Allen and State of Indiana, have invented certain new and useful Improvements in Pumps, of which the following is a specification.

This invention relates to pumps of the 10 class known as the reciprocating piston type, and the principal object of this invention is to provide a simple, compact and easily operated pump of this type which is effective and efficient in operation, and adapted 15 to discharge a continuous and uniform or approximately uniform stream of liquid without change in the direction of movement of the piston operating means.

Another object of the invention is to provide 20 a pump of the class described in which a constant direction of movement is imparted to a shaft, which in turn effects the movement of reciprocable plungers without the medium of racks or gears.

Another object of the invention is to provide 25 means to vary the length of the stroke of the pistons or plungers.

Another object of the invention is to vary 30 the duration of the power stroke without affecting the operating means, in other words, to lengthen the duration of the power stroke and to correspondingly reduce the duration of the return stroke in order that the power stroke of two reciprocating pumps may 35 overlap to produce a continuous flow and pressure on the liquid pumped, whereby both rate of flow and pressure are substantially uniform throughout the cycle of movements of the pump.

To the attainment of these ends and the accomplishment of other new and useful objects, as will appear, the invention consists in the features of novelty in the construction, combination and arrangement of 45 the several parts generally shown in the accompanying drawings and described in the specification, but more particularly pointed out in the appended claims.

In the drawings, Figure 1 is a side elevation 50 of a pump constructed in accordance with the principles of our invention; Fig. 2 is a diagram illustrating the comparative lengths of the power and return strokes of a pump constructed in accordance with the

principles of our invention; it also shows 55 the pressure or flow of the liquid to be pumped substantially the same at all times; Fig. 3 is a detail view of one of the pivoted members which connects the crank of the pump to one of the operating plungers; Fig. 60 4 is an enlarged side elevation of the pump operating mechanism; Fig. 5 is a plan view of the pump operating mechanism; Fig. 6 is a detail side elevation, partly in section, of the pump cylinders and operating valves; Fig. 7 is a detail sectional view of the head member, showing the discharge chamber; and Fig. 8 is a plan view of the top of said head member.

It has been the practice in constructing 70 pumps, and particularly self-measuring pumps for discharging the liquids from tanks and the like, to make use of rack and pinion movements for operating the piston or pistons. In single cylinder pumps a 75 pinion connected with suitable operating means as a handle has been used in mesh with a rack secured to the piston. The result of such construction is that during one stroke of the piston the liquid to be pumped 80 flows into the pump barrel or cylinder during which time there is no discharge and therefore only each alternate stroke of the pump piston would be effective to discharge liquid from the pump. Such construction 85 has made it necessary to stop the operating means at the end of each stroke of the piston and reverse the movement of the same, which also results in considerable loss of 90 time in the pumping operation with the attendant loss of energy due to the necessity for reversal of the operating means. When 95 it has been sought to overcome these difficulties by the use of double cylinder pumps, each piston of which is provided with a rack and the racks in mesh with a common gear or pinion, the racks have been associated with the operating gear or pinion on opposite sides thereof so that the pump pistons or plungers will be operated in opposite 100 directions, the piston or plunger of one cylinder discharging while the piston or plunger of the other cylinder is on the return movement with the liquid to be pumped flowing into the vacuum within the cylinder 105 created by the return movement of the piston. This construction insures that one or the other of the cylinders shall be constantly

discharging liquid while the operating mechanism is moving, but does not obviate the necessity for reversing the driving mechanism and the attendant loss of time in stopping of the flow of liquid necessary to such reversal of the operating means. Therefore, while this last-mentioned construction of double cylinder pump has proven to be more efficient than a single cylinder reciprocating pump, it is defective for the reasons stated in not providing pumping means which will discharge a continuous and uniform or approximately uniform stream of liquid.

The present invention proposes that in place of providing a single reciprocating pump driven by driving gear and rack or double cylinder pumps or pump cylinders with pistons driven by the same mechanism, that a plurality of separate single-acting pump sections shall be employed which are suitably connected with operating cranks driven constantly in one direction from a common source of power and so arranged that the power strokes of the pumps overlap, resulting in a continuous supply of fluid at a substantially constant pressure. When only two pumping sections are employed, as herein particularly shown and described, it becomes necessary to provide means whereby the power strokes of each of the sections be prolonged and the return stroke be correspondingly reduced, the entire operation constituting a complete cycle of operations.

A further object to be attained by the present invention is to provide means not only for varying and adjusting the duration of both the power and return stroke, but also to provide means for varying the length of the stroke. A slight variation of the length of the stroke is very frequently desirable for the reason that in pumps of this class it is customary to proportion them so that a complete stroke of the piston or plunger in the cylinder will discharge a specified amount or quantity of liquid. By means of the adjustment herein described this amount may be regulated to a nicety.

Referring now more particularly to the drawings and in the present exemplification of the invention, as illustrated by Fig. 1, a pump constructed in accordance with the principle of the invention is shown mounted upon a supply pipe 10 which is provided with an adjustable collar 11 positioned near the ground or support for the pump, in order that it may be stayed in position and protected about the base of the pipe.

The pump proper consists of a plurality of separate pump cylinders 12 one of which is shown in section in Fig. 6. These pump cylinders are provided at the bottom with a base member 13, which is secured to the supply pipe 10, and which forms a common inlet chamber for all of the pump cylinders.

At the top of the pump cylinders there is provided a top member 14, which constitutes a common discharge chamber or header for all of the pump cylinders. These two members 13 and 14 are secured together in any suitable manner, such, for example, as by means of the rods 15, which pass through suitable openings in each of the said members, and the ends of which are threaded to receive the nuts 16. The pump cylinders 12 are suitably positioned between these members 13 and 14, and are held in position by means of the rods 15. Surrounding the cylinders is a casing 17 which forms a suitable covering for the pump cylinders.

Interposed between each of the pump cylinders and the inlet chamber in the member 13, and suitably held in position by the said member, are valves, one of which is shown in section in Fig. 6. This valve comprises a valve seat member 18, with a central hub portion 19, around which are openings, and with an outwardly extending flange portion 20. A valve member 21 having a stem 22 and an adjustable nut 23 mounted thereon, is adapted to be positioned in said hub portion, and to move freely therethrough, being limited in its upward movement by the position of the nut 23, and the normal position of the valve member 21 being upon the valve seat member 18. To secure the valve seat member in position an internally threaded opening is provided in the bottom member 13, in which the member 18 is placed, and packing material 24 being interposed between the member 18 and the bottom member 13, and an externally threaded sleeve 25 is screwed in the said opening against the flange portion 20 of the valve seat member to hold it in place. This valve is disposed so that it will permit the ingress of fluid to the pump cylinder, and will prevent the egress of fluid therefrom.

A piston or plunger is disposed within each of the pump cylinders, and is reciprocally movable therein. Each plunger in the present exemplification of the invention comprises a rod 26 formed with a shoulder 27, and threaded at its lower end to receive a nut 28. Positioned on the rod 26 and bearing against the shoulder 27, is a plunger member 29, having a hub portion 30 and fitting the inside of the cylinder closely with openings therethrough between the outer edge or rim and the hub portion 30. The upper edges of the member 29 are formed with edges 31 and 32 on the hub portion and the outer rim portion respectively. A valve seat member 33, slidable upon the rod 26, is positioned above the shoulder 27, and engages the valve seat edges 31 and 32 to form a closed plunger. The valve seat member 33 being slidable upon the rod 26 may rise from its engagement with the valve seating edges and its movement in an upward direction

with respect thereto is limited by a pin 34, or other suitable means secured to the rod 26. The lower portion of the member 29 is preferably formed with a diameter somewhat less than the diameter of the cylinder and with a groove or depression 35. A clamping member 36 is positioned on the rod 26, below the member 29, and interposed between these members is a packing material 37 which engages the walls of the cylinder, and is preferably formed into such engagement by a suitable resilient member 38, the packing material being held in position between the two members 36 and 29 by means of the nut 28, which is threaded upon the rod 26. The member 36 is also apertured surrounding its material hub portion, so that when the valve member 33 is raised from the valve seats direct communication is turned through the plunger to permit the flow of fluid therethrough. The disposition of the valve members is such that upon the down stroke of the plunger the valve member 33 is raised from its seats, and upon the up motion of the plunger the valve member 33 is retained in position upon its seats. It is manifest that the actions of the valve in the plunger and the valve at the bottom of each cylinder are directly opposite; in other words, the action of one is the reverse of the other.

To provide a fluid tight construction about each rod 26, the top member 14 is formed with bosses 39, through which the rods 26 extend. A gland 40 is positioned about each rod 26, seated in the boss 39, and held in position by a packing nut 41, suitable packing material 42 being disposed in the space between the boss and the gland. The portion of the rod 26 which is movable through the packing head is preferably provided with a shell or sleeve 43, of material that will not corrode so readily, thereby maintaining a smooth surface where the rod slides through the packing material.

Inside of the head member 14, surrounding each of the rods, is a depending portion 44, which extends downwardly in the discharge chamber. An outlet or discharge opening 45 is disposed in the outer wall of the head member 14, at such a position that the lower edge of the opening will be above the depending portions 44, which surround the rods 26. A partition 44' is disposed in the member 14 between the portions 44 and the outlet opening 45 which depends from the top of the member. The object of this construction is to provide a space in the head member or the discharge chamber above the lower edge of the partition 44' and above the lower end of the depending portions 44, to form an air chamber for permitting the expansion of fluid in the cylinder, and in the discharge chamber. This will form a fluid seal for the air cham-

ber and will insure that the head of the fluid in the pump and in the discharge chamber at each time will be a certain amount providing there is no leakage past the plungers, and even if the discharge nozzle remains open. Connected to this discharge opening 45 is a nozzle or discharge faucet 46 (see Fig. 1).

Disposed above the pump cylinders and preferably secured thereto by means of the rods 15 and nuts 16 (see Figs. 1 and 6) is a housing 47, which contains the plunger operating mechanism. This mechanism comprises a crank shaft 48, provided, in the present exemplification of the invention, with two cranks 49 and 50, preferably disposed opposite to each other or at an angle of 180 degrees. This crank shaft is suitably mounted at its ends in the housing 47, one of the ends, as 51, being longer than the other, and extending through the housing. A gear 52 with an extending sleeve portion 53, is mounted upon the shaft 51, and preferably inside of the housing, with the sleeve portion 53 extending outwardly. A crank handle 54 is attached to the hub or sleeve portion 53 of the gear 52 and is secured against rotation on the hub or sleeve portion 53 by means of a key 55, and against lateral movement by means of a set screw 56. The hub or sleeve portion 53 is preferably bored out so that it will slip freely on to the shaft 48, and is connected to the crank shaft by means of a key 57. The key way in the hub of the gear 52 is made wider than the key 57, so that about 5 degrees backlash between the gear and the crank shaft is obtained; that is, the gear 52 may be rotated back and forth through about 5 degrees without rotating the crank shaft; the object of this construction is to provide means for releasing the clutch in a meter designated generally by the reference numeral 57, to which the gear 52 is connected, and which constitutes no part of the present invention. The construction and operation of this feature, however, will be described and claimed in another application. It will be evident, however, that as the crank handle 54 is rotated the crank shaft 48 and the cranks 49 and 50 will be correspondingly rotated.

At one side of the housing, and preferably at a point below the center of the crank shaft 48, is an eccentrically mounted shaft or pin 58. This pin 58 is provided with a bearing support 59, at one end and at the other end is provided with means for adjusting the position of the pin and for holding the pin against rotation after the adjustment has been made. These means comprise a squareheaded portion 60, by means of which the pin may be rotated, and for securing the pin against rotation there is provided a clamping collar 61, secured to the shaft by means of a key 62, the collar being

made to turn in the machined hole 63, which, properly speaking, forms the bearing for this end of the shaft. A screw plate 64 is threaded on its outer circumference, so 5 that it may be screwed into position in a threaded opening 65 in the housing. This screw plate 64 is provided with clamping screws 66 which are adapted to engage the clamping collar 61, and to hold it in position.

10 A cap 67 is provided for the threaded opening 65, which is adapted to prevent the exposure of the adjusting means of the pin 58. This cap is preferably provided with a per- 15 forated lug 68, which is in proximity to a lug 69 on the housing 47, so that a seal 70 may be attached after the pin 58 has been properly adjusted, thereby preventing an unauthorized person from tampering with 20 the adjustment of the pin without detection. Pivottally mounted upon this pin 58 are levers or members 71 and 72, preferably U shaped in construction, as shown more clearly by Figs. 3 and 4, one of them being 25 shown in section in Fig. 5. Each of these members is mounted at the rounded end of the pin 58, with the ends extending on opposite sides of the cranks 49 and 50, so that the cranks in rotating will produce an up 30 and down movement of each of the members about its point of pivotal support. The extending sides of each member form a guideway or slide 73 (see Figs. 3 and 4), in which a bearing for one of the cranks is 35 slidale. This bearing preferably comprises a pair of segments 74 which surround the portion of the crank which may be referred to as crank pin, and the segments may be secured together by means of the pins 75. 40 From this it will be evident that as the cranks are rotated the bearing members will slide in the guideway 73, causing thereby an up and down movement of the members 71 and 72 about their point of pivotal support. 45 Each of the members 71 and 72 is connected by means of a bar 76 to one of the pump plunger rods 26. Any desired or suitable pivotal connections may be made between these members, for example, as shown 50 in Fig. 4, it being necessary only to provide a freely rotatable pivotal connection. It is, therefore, evident that as the crank handle 54 is rotated the plungers in the pump cylinders will be reciprocated in succession. 55 Each of the levers 71 and 72 is preferably provided with an oil box 77 on the top side. These oil boxes supply oil to the various moving parts, through suitable openings, and a tube 78 is preferably provided 60 in the housing 47 above each of the levers, so that the oil boxes may be filled from the exterior of the housing.

65 By reference to Fig. 3, it will be evident that with this construction the duration of one of the strokes of each of the piston rods

26 will be greater than the other stroke. This will be clearly seen by reference to Fig. 3, because of the fact that the plunger will be at the bottom of its stroke when one of the pivotally mounted members is at its 70 lowermost position, and will be at the top of its stroke when the member is at its uppermost position. These respective positions are indicated by the dotted lines 79 and 80, which represent the center line of 75 one of the members with respect to the circle described by the center of one of the crank shafts. In other words, the respective duration of each of the strokes of one of the plungers is represented by the portion of 80 the circle inclined between the two points of tangency. In the present construction the power stroke is of longer duration than the return stroke of the plunger. By varying the distance of the center of the pivotal pin 58 from the center of the crank shaft 48, the duration of the strokes may be varied. For example, by moving the point of pivotal support toward the center or axis of the crank shaft, the longer stroke is made of a 85 greater duration and the shorter stroke of a less duration, and by increasing the distance between the point of pivotal support and the center line of the crank shaft, the longer stroke is reduced in duration and the 90 shorter stroke is correspondingly increased in duration. This, in a pump having two pumping sections, as described, in the present exemplification of the invention, causes the power strokes of the two pumps to overlap so that they will maintain a constant 95 flow of fluid and a constant pressure on the discharge chamber.

100 The operation is graphically shown in Fig. 2, in which the curve A—B—C—D represents the power stroke of one of the pumps, and the curve E—F—G the power stroke of the other pump. These curves are plotted with the vertical distance representing the pressure or flow of the liquid and with the horizontal distance representing the time or duration. The entire distance as shown represents a complete cycle of operations; that is, corresponding to a complete rotation of the crank handle or 360 degrees. As the power strokes of both of the pumps are of greater duration than the return strokes, it is evident that the power strokes of both pumps must overlap, and that in overlapping the quantity of liquid pumped by each pump must be added, as at H so that for a complete cycle of operations the amount of liquid pumped would be represented by the curve A—H—F—I—D, 110 from which it is evident that the flow of liquid would be practically constant, for the reason that a straight line might be drawn from one end of the diagram to the other, which would be at all times in close proximity to all portions of the last named 115 120 125 130

curve. It should also be noted that the cycle of operations may be commenced at any time and stopped at any time, with the result that the amount of liquid pumped during the time elapsing will be substantially constant, and particularly is this true when any equal division of a complete cycle of operations is performed, because the amount pumped is so near an approximation to a constant amount as to amount to a continuous discharge of the same amount.

Another feature of the invention is that by varying the position of the pivot pin 58 in a vertical direction with respect to the 15 crank shaft, the length of stroke of the plunger may be correspondingly diminished or increased. In the present exemplification of the invention since the axis of the pivot pin 58 is disposed below the axis of the 20 crank shaft, the movement of the pivot pin about its eccentric bearing so that the center of pivotal support is lowered, will result in an increase in the length of the stroke of the plunger and the movement in the opposite direction will result in a diminishing 25 of the length of the stroke of the plunger. This is a very valuable feature in pumps of this class, for the reason that it is sometimes desirable to vary the amount pumped 30 during a single stroke, because of the inaccuracies of construction, and for the reason that it is usually desirable to pump a specified amount upon a single rotation of the crank handle. By the simple variation of 35 the position of the pivot pin 58 considerable adjustment is permitted in either direction. From this it will be evident that the length 40 of the strokes of both of the plungers, as well as the duration of the power and return strokes, may be varied by a single variation of the position of the pivot pin, and that by this variation any desired length 45 and duration of stroke may be obtained within the limits permitted by eccentricity of the pivot pin.

While we have thus described the preferred embodiment of our invention, it is evident that others skilled in the arts to which this appertains may make various changes in the 50 construction, combination and arrangement of the several parts which constitute our invention without departing from the spirit and scope thereof.

What we claim is:

55 1. The combination in a single action reciprocating pump, of a rotatable crank, a yoke in which the crank slides as the crank rotates, a piston connected to the yoke and an eccentrically adjustable pivot pin upon 60 which the yoke is mounted on one end, the pin being adjustable to vary the length and to adjust the duration of the effective power stroke at the same time.

65 2. The combination with a single action reciprocating pump, of an adjustable eccen-

tric means to vary the length of stroke of the pump plunger, and means to secure the eccentric in position for any variation.

3. The combination with a single action reciprocating pump, of an eccentric to vary 70 the length and the comparative duration of the power stroke of the pump plunger with respect to the return stroke.

4. The combination with a single action reciprocating pump, of means to simultaneously vary and adjust the length and duration of the effective power stroke by a single operation.

5. A continuous flow pump comprising a plurality of single action reciprocating pumps, a common discharge chamber for the pumps, and an eccentric to vary the 80 length and duration of the strokes of each of the pumps by a single operation whereby the power strokes overlap to maintain uniform pressure in the discharge chamber.

6. A continuous flow pump comprising a plurality of single action reciprocating pumps, a common discharge chamber for the pumps, an eccentric to vary the length 90 and duration of the pump strokes, and means to secure the eccentric in position for any variation.

7. A continuous flow pump comprising a plurality of single action reciprocating pumping elements, means to operate the pump plungers, and means to vary the length of strokes and the duration of the power and return strokes, the operating means being independent of said varying 100 means.

8. A continuous flow pump comprising a plurality of single action reciprocating pumping elements, cranks disposed at an angle to each other and operative together, an eccentrically adjustable pivot pin, and yokes mounted at one end on the pin, each having a slideable connection with one of the cranks and directly connected to one of the pumping plungers to communicate the crank action to the plungers and to cause the power strokes of the pumps to overlap whereby a continuous flow of liquid results.

9. A continuous flow pump comprising two single action reciprocating pumps, a common discharge chamber for the pumps, means to operate the pumps, an eccentrically adjustable pivot pin, and yokes mounted at one end on the pin, each having a slideable connection with one of the cranks, and directly connected to one of the pump pistons to cause the power strokes of the two pumps to overlap, thereby obtaining a continuous supply of fluid in the discharge chamber at a substantially constant pressure, the return 115 strokes of the pumps being of shorter duration than the power strokes.

10. The combination with a single-action reciprocating pump, of a rotatable crank, a member pivoted to the pump in which the 120

crank is slidable for reciprocating the pump, and an adjustable eccentric pivot pin for the member mounted at the side of the pump and movable vertically to vary the length 5 of stroke of the pump.

11. The combination with a single-action reciprocating pump, of a rotatable crank, a member pivoted to the pump in which the crank is slidable for reciprocating the pump, 10 and an adjustable eccentric pivot pin on which the member is pivoted at one side of the pump, movable toward and from the pump to vary the duration of the effective power stroke with respect to the return 15 stroke.

12. In a continuous flow pump, the combination with reciprocable plungers, of a rotatable crank, and a member adjustably pivoted at one end and having connection with 20 the crank and the plunger and being pivoted below the axis of the crank whereby the up stroke of the plunger is made of longer duration than the down stroke.

13. In a pump of the class described, the 25 combination with a reciprocable plunger, a rotatable crank, of a member adjustably pivoted at the side of the crank for movement in all directions and having connection with the crank and the plunger whereby the 30 length of and duration of the strokes of the plunger may be varied by such movement.

14. In a pump of the class described, the combination with a reciprocable plunger, of a rotatable crank, an adjustable eccentric 35 pivot pin, a member having one end pivotally mounted on the pin and engaging the crank, means to connect the plunger to the said member, whereby the rotation of the crank will effect the operation of the plunger, the adjustment of the pin being adapted 40 to vary the length and duration of the plunger strokes.

15. In a pump of the class described, the combination with a reciprocable plunger, of 45 a rotatable crank, an eccentrically mounted pivot pin, a member having one end mounted on said pin, the other end being forked and portions thereof extending on opposite sides of the crank pin, the said member being 50 adjustable upon the said pivot pin with respect to the crank whereby the length and

duration of the stroke may be varied, and means to connect the said member to the plunger.

16. In a pump of the class described, the 55 combination with a reciprocable plunger, of a rotatable crank, an adjustable eccentrically mounted pivot pin, a U-shaped member with the rounded portion mounted on the pin for adjustment in any direction to vary the 60 length and duration of its movements, and the ends extending on opposite sides of the crank, the said crank sliding between the ends as the crank is rotated, thereby oscillating the member about its point of pivotal 65 support, and means to connect the member to the plunger.

17. In a pump of the class described, the combination with a reciprocable plunger, of a rotatable crank, an adjustable eccentrically mounted pivot pin, a U-shaped member with the rounded portion mounted on the pin and the ends extending on opposite sides of the crank, and forming a slide therefor, 70 bearing members surrounding the crank pin 75 and movable in the slide, the rotation of the crank causing the bearing members to move in the slide and to move the said member up and down about its point of support, and means to connect the said member to the 80 plunger to reciprocate the plunger.

18. In a pump of the class described, the combination of a member forming a common discharge chamber, a plurality of rods movable therein and through the top of said 85 member, the said member being provided with a discharge opening, depending portions surrounding said rods and a partition extending downwardly from the top of the member between the opening and said depending portions below the bottom of said 90 discharge opening to form a fluid seal for said chamber.

In testimony whereof we have signed our names to this specification, in the presence 95 of two subscribing witnesses, on this 8th day of August, A. D. 1912.
